Primary Examiner — Catherine R Oliver-Garcia(74) *Attorney, Agent, or Firm* — Knobbe, Martens, Olson & Bear, LLP(57) **CLAIM**

The ornamental design for a reel component, as shown and described.

DESCRIPTION

FIG. 1 is a front top perspective view of a reel component showing the new design;

FIG. 2 is a rear bottom perspective view thereof;

FIG. 3 is a rear elevational view thereof;

FIG. 4 is a front elevational view thereof;

FIG. 5 is a left elevational view thereof;

FIG. 6 is a right elevational view thereof;

FIG. 7 is a top plan view thereof; and,

FIG. 8 is a bottom plan view thereof.

The dash-dash broken lines in FIGS. 1-8 show portions of the reel component which form no part of the presently claimed design.
